UNITED STATES PATENT OFFICE.

ELIZABETH A. DAVIS, OF MOUNT VERNON, NEW YORK, ASSIGNOR TO BLANCK & CO.
INC., OF NEW YORK, N. Y.

DESIGN FOR EMBROIDERED LACE.

Application filed January 23, 1925. Serial No. 12,115. Term of patent 3½ years.

To all whom it may concern:

Be it known that I, ELIZABETH A. DAVIS, a citizen of the United States, residing at Mount Vernon, Westchester County, State of New York, have invented a new, original, and ornamental Design for Embroidered Lace, of which the following is a specification; reference being had to the accompanying drawing, forming a part thereof.

The figure is a plan view of embroidered lace showing my new design.

I claim:

The ornamental design for embroidered lace as shown.

In testimony whereof I affix my signature.

ELIZABETH A. DAVIS.
